UNITED STATES PATENT OFFICE.

HARRY K. SMITH, OF ARCHER, IOWA.

GATE-LATCH.

SPECIFICATION forming part of Letters Patent No. 764,076, dated July 5, 1904.

Application filed February 23, 1904. Serial No. 194,741. (No model.)

To all whom it may concern:

Be it known that I, HARRY K. SMITH, a citizen of the United States, residing at Archer, in the county of O'Brien and State of Iowa, have 5 invented certain new and useful Improvements in Gate-Latches; and I do hereby declare the following to be a full, clear, and exact description of the invention, such as will enable others skilled in the art to which it appertains to make 10 and use the same, reference being had to the accompanying drawings, and to the figures of reference marked thereon, which form a part of this specification.

My invention relates to improvements in 15 gate-latches, and has for its object strength and durability, together with simplicity of construction.

Improved details in the construction and arrangement of the various parts of the invention 20 will be apparent from the following description and claim when read in connection with the appended drawings, in which—

Figure 1 is a side elevation of a gate provided with my latch. Fig. 2 is an edge view 25 thereof. Fig. 3 is a horizontal section on the line 3 3 of Fig. 1. Fig. 4 is a horizontal section on the line 4 4 of Fig. 1. Fig. 5 is a top plan view of the keeper. Fig. 6 is an elevation thereof.

Referring specifically to the drawings, 7 indicates a gate which is hinged to a post 7^a to 30 swing in either direction.

At 8 is indicated a post which carries a keeper 9. The latter comprises a rectangular plate 35 or casting having on its face a projection 9^a formed with a central notch 9^b and beveled or slanting to each end. To fasten the keeper, a bolt 10 extends through a slot 9^c in the keeper and through the post, the slot being counter- 40 sunk to receive the head of the bolt. The purpose of the slot is to permit lateral adjustment of the keeper. Additional fastening means comprise screws, which extend through holes 10^a near the lower corners of the keeper- 45 plate and into the post.

Around the end boards 7^b of the gate a strap 11 is secured, which has horizontally-projecting arms 11^a, and along the edge of the gate opposite the post 8 a strip 12 is secured, hav-

ing hooked ends 12^a to receive the ends of a 50 flat spring-strip 13, which forms the latch. Bolts 14 pass through the hooked ends 12^a of the strip 12 and through the latch 13 into the gate, whereby the parts are secured together. To permit movement of the latch 13, it is slot- 55 ted, as at 13^a, through which slots the bolt 14 passes. The arms 11^a have elongated vertically-alined slots 11^b, through which the latch 13 extends, and which guide its movement back and forth when in use. The latch 13 60 normally projects outwardly and lies in the notch of the keeper when the gate is closed. The keeper is so positioned on the post that the projection 9^a extends between the arms 11^a when the gate is closed, and that part of 65 the latch which engages the keeper is rounded, as at 13^b, to facilitate its movement along the beveled portion of the keeper. To re- 70 tract the latch and permit opening of the gate, I provide a hand-lever 15, which is pivoted at its lower end to one of the horizontal slats or boards 7^c of the gate and carries a rod 16, the outer end of which engages a link 17 around the latch between the arms 11^a. The link extends through registering slots in the 75 strap 11 and strip 12. There are two end boards 7^b, between which the horizontal slats or boards 7^c of the gate extend and are se- 80 cured. This spaces the end boards, and the rod 16 extends and operates between them, as shown in Fig. 3. It will be seen that when the lever is swung rearwardly the latch will 85 be retracted from the notch, which permits opening of the gate. The upper end of the lever extends some distance above the gate to permit operation of the latch by a mounted 90 person without the inconvenience of dismounting. The lever also has a handhold 18 for ordinary use. The rod 16 is secured to the hand- 95 lever by a bolt 19, and by providing the lever with a number of bolt-holes, as shown, the parts may be properly adjusted. Near the upper end of the gate a strap 20 is secured, under which the hand-lever extends and whereby its movement is guided. At 21 is indicated a bearing-plate, which is secured to the gate 95 and has a projecting stud 21^a, on which the hand-lever is pivoted. A bolt 21^b extends

through the stud and through a slot 21^c in one of the slots 7^c. This slotted construction permits the proper adjustment of the hand-lever with respect to the other parts of the device.

5 The operation of the latch is very simple, it being necessary only to swing the hand-lever rearwardly, after which the gate can be pushed open. When the gate is shut, the latch will strike the beveled portion of the 10 projection on the keeper, which will force it into the notch and in which it will be held by its spring. The gate swings both ways and can be opened and closed from either side. If any of the parts become loosened from wear 15 or otherwise, they can be readily adjusted, whereby the latch can be kept in good order at all times.

Having thus described my invention, what

is claimed as new, and desired to be secured by Letters Patent, is—

20 The combination with a gate and gate-post, of a keeper on the post, a strip along the edge of the gate opposite the keeper, and having hooked ends, a spring-latch loosely secured therein, horizontally-projecting arms on the 25 gate and having vertically-aligned slots through which the latch extends, and a hand-lever pivoted to the gate and connected to the latch for operating the same.

20 In testimony whereof I have affixed my signature in presence of two witnesses.

HARRY K. SMITH.
